OF BROOKLYN, NEW YORK

METHOD OF REFINING SUGAR

Application filed March 4, 1926. Serial No. 92,102.

My present invention relates to methods of treating saccharine fluids, particularly for the refining of sugar juices and melts, syrups, affinations and other "run-offs", and molasses, and aims to devise methods of the general character specified which are simple and convenient to practice, which result in certain conveniences in operation permitting equivalent economies in the practice of the methods 10 of the present invention, and which result in savings in fuel and labor charges which are important items in the cost of refining saccharine fluids, particularly of the classes referred to above. The methods of the present 15 invention possess other conveniences in operation and result in other economies in part pointed out in detail hereinafter and in part obvious to those skilled in the art to which the present invention relates. While not 20 limited thereto, my present invention finds particularly successful application in connection with the refining of such saccharine fluids as sugar juices and melts, syrups, affinations and other "run-offs", and molasses 25 by the use of activated vegetable carbons, particularly the highly activated vegetable carbon known to the trade as "Suchar".

In the accompanying specification I shall describe several illustrative embodiments of 30 the methods of the present invention. It is, however, to be clearly understood that my invention is not limited to the specific forms thereof herein described for purposes of illustration only.

Before describing the aforesaid illustrative embodiments of the methods of the present invention in detail, it may be desirable briefly to point out the factors in the economies 35 of the refining of saccharine fluids, such as sugar juices, and melts, syrups, affinations and "run-offs", and molasses, especially by the use of activated vegetable carbon, towards which the methods of the present invention are particularly directed in the interest of 40 improvements and equivalent economies in operation. One of the largest items of expense in the refining of saccharine fluids, such as sugar juices and melts, syrups, affinations and other "run-offs", and molasses, is the fuel 45 item. The fuel item is, in fact, generally

about equal in importance to the labor item, which latter item is only exceeded in the usual case by the expense of the "sugar package" item. This fuel item may be reduced by filtering the affinations and certain other "run-offs", thereby reducing the amount of steam required by the "boil-backs", or such fuel item may be reduced by sending to the vacuum pans a filtered melt of increased density. 55

Another item of expense in the refining of saccharine fluids, such as sugar juices and melts, syrups, affinations and other "run-offs" and molasses, is the handling and revivifying of the vegetable carbon used. Of course, where the carbon is such that it cannot be 60 revivified, this item of expense becomes very considerable and in some instances may indeed become prohibitive. On the other hand where the carbon may be revivified, as in the well known case of the highly activated vegetable carbon known to the trade as "Suchar", which is fully described and which is claimed in the copending application of John J. Naugle, Ser. No. 633,640, filed April 21, 1923, entitled "Method of treating carbonaceous 65 material in an electric furnace or the like", used in the "Suchar process", this expense becomes a relatively moderate one but is still non-negligible, being dependent upon the quantity of carbon required for the purification. Any economically sound system of utilizing the "Suchar" or other activated vegetable carbon or other purifying filtering medium which will reduce the quantity of carbon required for the treatment of a given unit 70 of weight of sugar solids contained in the saccharine fluids being treated will correspondingly reduce the refining cost. 75

"Suchar" is the name by which is known in the market the highly activated vegetable 80 carbon of great decolorizing, purifying and filtering powers and which may, after use, be completely revivified with full restoration of its original decolorizing, purifying and filtering powers by suitable treatment in an 85 electric furnace. "Suchar" may be prepared by treating leached carbonized lignin residues or "leacher refuse," obtained by carbonizing the alkaline liquors derived as a by-product from the manufacture of wood pulp 90 100

by the "alkali" or "soda" process, in an electric furnace for 15, 20 or 30 minutes, more or less, at a temperature from about 750 to about 950 degrees C., in the presence of steam, carbon dioxide or a mixture of steam and carbon dioxide, preferably by the passage of an electric current through the raw material in a suitable electric furnace in the presence of the treating gas or gases referred to, after which the preliminarily treated material may be subjected to a further treatment at a temperature of about 350 to 450 degrees C. for thirty or forty minutes, also in the presence of steam, carbon dioxide or a mixture of steam and carbon dioxide, preferably also by the passage of an electric current therethrough in a suitable electric furnace in the presence of the treating gas or gases referred to, after which the material may be given an acid wash, as with a dilute solution of hydrochloric acid, washed with water in a suitable filter press or other suitable apparatus, dried, ground to suitable fineness, tested and bagged, when it will now be ready for use.

Still another item of manufacturing expense is the concentration of wash waters from the filters to which the suspension of the "Suchar" or other vegetable carbon in the saccharine fluid being purified is sent. While, by the use of the highly activated vegetable carbon known to the trade as "Suchar", this item of expense is substantially reduced and is in fact eliminated when refining by filtering the sugar melt only, because all wash waters are needed to dissolve further incoming unrefined sugars, more wash waters, and particularly more wash waters of lower purity, will be obtained when liquors other than sugar melts are filtered to remove from suspension therein the "Suchar" or other purifying filtering medium.

As low purity wash waters cannot be used for melting sugar, an expensive evaporation station, probably a multiple effect evaporation system, might be required in the latter case. It therefore becomes highly important to use such a system of refining the saccharine fluids by the use of "Suchar" or other vegetable carbon or other purifying prefiling medium as will yield the least volume of wash waters. Under certain conditions such wash waters may be used for further dilution of low grade saccharine liquors to be filtered, and if such water is no more than the volume of water which would be needed for such melting, no evaporators at all will be necessary at this stage of the process.

A further consideration of considerable economic importance is that a diminution in the amount of fuel required for the refining operation will diminish the required steam boiler and vacuum pan capacities nec-

essary for refining operations of a given capacity. From many points of view, especially from the point of view of the most favorable installation of the process for refining sugar juices and melts, syrups, affinates and other "run-offs," and molasses known to the trade as the "Suchar process", this latter factor is a very important consideration. This is not only because the installation cost of converting a raw sugar factory into a refinery would be lessened, thereby requiring a lower initial outlay for this purpose, but also because an installation, otherwise of doubtful economic success, might be converted into one of certain economic success by reason of the lessened equipment capacity made possible by the application of the principles of the present invention.

I have discovered that many economies along the lines indicated as being desirable in the foregoing portions of this specification may be effected by treating by the batch method batches of saccharine fluids, of any of the types indicated above, having various or different densities, these batches of saccharine fluids of various densities being treated by batches of "Suchar" or other vegetable carbon or other purifying and filtering medium of varying or different degrees of activation or purifying power. In general, in this invention, filtering agents, such as "Suchar" or other vegetable carbon, or other filtering and purifying medium, of relatively low degrees of activation or purifying powers are used on batches of saccharine fluids of the general character specified above of less purity, or of less density, or on batches of saccharine fluids of the general character specified above being both of less purity and of lower density. On the other hand, filtering agents, such as "Suchar" or other vegetable carbon, or other filtering and purifying medium, of relatively high degrees of activation or purifying powers, are used on batches of saccharine fluids of the general character specified above of higher degrees of purity, or of higher density, or on batches of saccharine fluids of the general character specified above being of higher degrees of purity and of higher densities.

Expressed in another way, the greater number of the economies referred to as being desirable to be obtained in the earlier portions of this specification may be obtained by prefiling a batch of relatively low density unfiltered and undecolorized saccharine fluid of a relatively low degree of filterability with a batch of almost completely spent "Suchar" or other vegetable carbon or other purifying and filtering medium, after which the batch of saccharine fluid so prefilled may have its density increased by dissolving therein a certain amount of sugar solids or adding a more concentrated syrup thereto, after which the partially decolorized batch of in-

creased filterability and purity and increased density may be treated with a predetermined amount of a more active or less spent "Suchar" or other vegetable carbon, or other purifying and filtering medium, and finally the batch of saccharine fluid thus obtained may have its density further increased by the addition of still another portion of sugar solids or of relatively concentrated syrup and the batch of still higher degree of decolorization and filterability and of still higher density thus obtained may be treated with a predetermined weight of virgin or relatively highly activated "Suchar" or other carbon or other purifying medium.

In other words, I apply the principles of multiple density filtration in accordance with the methods of the present invention on the counter-current basis of operation, regulating the densities of successive batches of saccharine fluid until the finally purified melt is obtained, to obtain batches of successively increasing densities and successively increasing degrees of purity, decolorization and filterability, increased densities corresponding generally to increased degrees of purity, decolorization and filterability, obtaining this result by successive treatments with batches of carbon of increasing degrees of activation. In accordance with the principles of the present invention, the spent or partially spent "Suchar" or other vegetable carbon or other purifying filtering medium obtained from the filters after treating one batch of saccharine fluids in accordance with the principles of the present invention is used for the treatment of another batch of saccharine fluids of lower density and lower degree of purity than the batch which it has just been used to treat, unless the carbon is so spent that it should be sent, in the case of "Suchar", for example, to the revivifier.

One immediate result of this mode of procedure is the reduction of the amount of steam required by the evaporating pans in the formation of refined sugar, in the case, for example, where sugar melts are being treated in accordance with the principles of the present invention. In such a case, for example, if the melt was filtered and decolorized so as to be supplied to the pans at an increased density, corresponding to about 4° Beaumé or about 7.6° Brix higher than is feasible under the present practice, with crude oil at three and one-half cents per gallon, a saving would be effected of \$37,000 per annum in a refinery of a capacity of five hundred (500) tons of sugar a day, calculating on a basis of three hundred (300) days a year, or a resulting saving of 24.7 cents per ton of sugar produced. This saving of 24.7 cents per ton of sugar produced, in the specific example being given, would apply to any installation irrespective of its size. The foregoing economies result in part from the

fact that using a given quantity of "Suchar" or any other vegetable carbon or other filtering purifying medium, any ordinary saccharine fluid will filter more readily after it is totally or partially prefiltered.

Before describing one specific example carrying the principles of the present invention into effect, it may be desirable to elucidate further the principles and considerations on which the methods of the present invention are based. Using a given purifying and filtering medium, such as "Suchar", for example, a prefiltered sugar melt of a density of, say 29° Beaumé, which has already been prefiltered by the use of a given weight of semi-exhausted "Suchar", could have its density increased, say, to about 33° Beaumé by the addition of more original raw sugar being purified. The sugar melt of increased density could then be readily filtered through the same weight of "Suchar" in a less exhausted or virgin condition as the unprefiltered melt of lower density first referred to. These same considerations hold true even to a more marked degree of saccharine fluids of lower degrees of purity, such as molasses, "run-offs" and syrups, or any other saccharine liquors, as well as for the saccharine liquors customarily known as "melts", degrees Brix differing.

A carbon after having been used to filter and decolorize a sugar-containing liquor still has some capacity to filter and decolorize the same kind of a solution and, to a lesser degree, to decolorize the same general kind of liquor. Having already been used for such a purpose initially, its ability during its subsequent use for a similar purpose is substantially reduced. In some instances, as with affinities or even lower grades of saccharine fluids, the practical value of such a spent carbon is questionable unless unnecessarily large quantities of carbon are used or liquors are handled quite low in density. However, even in such cases, and certainly in the cases previously discussed, the use of such semi-exhausted or almost completely spent carbon or other filtering medium for prefiltration is advisable because to do so reduces the total quantity of carbon needed to purify a given quantity of sugar. Accordingly, the cost of handling, revivifying and replacing the carbon, together with the total cost of the installation, is correspondingly reduced.

In applying the principles of the present invention, it is desirable to so standardize the volumes and densities of the saccharine fluids treated in successive stages, in accordance with the principles of the present invention, that substantially similar weights of almost completely spent, semi-exhausted and virgin "Suchar" or other carbon or other filtering medium may be used for the corresponding batches to be treated. This facilitates the

manipulation of the successive batches of carbon of different degrees of activation. Of course, any carbon lost in processing may be replaced by virgin carbon supplied at the filtering station where virgin carbon is in use, which will be at the filtering station where batches of saccharine fluid of the highest degree of purity are preferably treated.

- 10 By using equivalent weights of carbon throughout the counter-current form of the method of the present invention as described above, which is the preferred form of the methods of the present invention, the system 15 will be unbalanced, as already referred to above, when conditions are such that the virgin carbon (being the carbon of highest degree of activation) is used on prefiltered saccharine fluids, preferably on saccharine 20 fluids which have been both prefiltered and also subsequently subjected to a partial purifying action (such liquors being the most easily handled); and the semi-exhausted carbon (of a lesser degree of activation) is 25 used on prefiltered saccharine fluids, preferably on saccharine fluids which have been subjected to a single prefiltration treatment with almost completely spent carbon (such liquors being not quite so easily handled as 30 the prefiltered and treated purified liquors already referred to, but being more easily handled than unfiltered liquors); and when substantially completely exhausted carbon (of the lowest degree of activation and, in 35 fact, possessing little if any decolorizing power) is used on incoming unfiltered liquors (offering the greatest filtration difficulties), all of the liquors treated being assumed to be of the same degrees Beaumé or the same density. The system becomes balanced only 40 when the densities of the various batches are so regulated, controlled and predetermined and the amounts or volumes of such batches are so regulated, controlled and predetermined 45 as to enable the substantially completely or partially spent carbon from one batch of fluid to be used for prefiltersing another bath of fluid of lower degree of purity and lower density.
- 50 A carbon, especially the vegetable carbon "Suchar", which has already been used with a sugar-containing liquor of definite quality and which, in its semi-exhausted condition, could not be economically used on the same 55 quality of liquor in unprefiltered condition, may still be used as an effective filtering and, to some extent, as an effective decolorizing medium when the density or degrees Brix of the unprefiltered solution to be treated 60 has been reduced. The "Suchar" or other carbon used in the last instance given may again be used quite effectively on the same quality of unprefiltered liquor of still a lower density of lower degrees Brix. With 65 batches of saccharine fluid of successively di-

minishing densities or diminishing degrees Brix, the same quantity of carbon, preferably "Suchar", whether in virgin or semi-exhausted condition, may be all the more effectively used as a decolorizing and purifying agent, on the basis of the weight of sugar solids contained in the batches of liquor being treated, when the densities or degrees Brix of said batches of liquor are reduced.

Furthermore, with the diminishing densities or degrees Brix of the batches of liquor being treated, a higher percentage of organic and inorganic impurities is removed. Moreover, less wash water is required to remove the sucrose retained by "Suchar" or other vegetable carbon or other filtering medium, in the form of a cake resulting from the filtration of a given quality of saccharine liquor, when a solution of lower density or lower degrees Brix has been filtered thereby. Under such conditions, also, the cake formed will be more porous, will retain less juice in it and will be more readily washable, for which reasons a lesser quantity of wash water will be required for washing the sugar values out of the filter cakes.

Turning now to one specific example of the methods of the present invention, I may, in practicing the method forming such specific example, proceed as follows: Sugar, washed or unwashed, as desired, is dissolved in water to form a melt of a density corresponding to from about 18 to about 28° Beaumé. The melt after straining is pumped from the melter through a heater to mixing tanks where semi-exhausted "Suchar" or other filtering medium is mixed with the melt and the mixture sent to the filters. The filtrate flows from the filters to another melter where more of the original sugar is added to raise the density of the melt to the density required for sending the melt of increased density to the sugar boiling pans. This melt of increased density, the density of which may be from about 28 to about 30° Beaumé, is sent to a second set of mixing tanks in which virgin or unused carbon is mixed with it. This melt of increased density is now filtered, the resulting filtrate being sent to the sugar boiling pans. The carbon, now once used, is in a semi-exhausted condition and may be used on melts of lower densities in accordance with the principles of the present invention as described above.

Of course, instead of being treated in two stages, the final melt may be passed through more than two stages, such as three, or even four or more stages, the purity and the density of the melt at successive stages increasing, while the degree of activation of the carbon likewise increases for melts of higher densities and higher degrees of purity just as the degree of activation of the carbon diminishes for melts of diminishing degrees of purity and lower densities.

For saccharine fluids of lower grades than

sugar melts, such as syrups, run-offs, molasses, etc., substantially the same mode of procedure may be carried out, except, of course, that lower densities of solutions are used in the case of liquors of increasingly lower grades. For instance, the first liquor filtered with semi-exhausted carbon may be of a density ranging from about 12 to about 25° Beaumé, while the second batch of liquor filtered through virgin carbon may correspond to from about 22 to about 35° Beaumé.

The foregoing constitute illustrative embodiments of the methods of the present invention. The advantages of the methods of the present invention, particularly as exemplified in the foregoing illustrative embodiments of the same, have already been pointed out earlier in this specification and may be briefly summarized as follows: By means of the application of the methods of the present invention, as exemplified in the foregoing illustrative embodiments of the same, numerous economies in steam for evaporation purposes and in the fuel required to generate such steam, as well as in boiler and power house capacities, may be effected. Such economies result in diminished overhead charges and render possible an appreciable saving per ton of refined sugar or other saccharine product, which saving adheres to each ton of sugar or other saccharine produce produced in accordance with the principles of the methods of the present invention, and is not dependent upon the size or capacity of the plant in tons of sugar, per day, produced therein. By means of the principles of the present invention, particularly as exemplified in the foregoing illustrative embodiments of the invention, many economies in the handling and manipulation of the "Suchar" or other vegetable carbon or other filtering and purifying medium are rendered possible. These economies permit proportional savings in carbon and handling expenses. Other advantages of the methods of the present invention will be obvious to those skilled in the art to which the present invention relates.

It may here be stated that the expression "sugar juices or melts, syrup, affinities or other 'run-offs' or molasses", includes, first, sugar juices whether derived from sugar cane or sugar beets; includes also sugar melts obtained by the melting or dissolving of sugar in water, whether the sugar is unwashed raw, washed raw or other sugar; and that the term "syrup" includes not only affinities or other "run-offs", but syrups obtained from other sources or by other means, including also all refinery liquors having a sugar content.

The drawing submitted herewith contains a single figure and comprises a diagram in the nature of a flow sheet exemplifying the process. The legends on the drawing make clear the different stages of the process so

that further description of the drawing is believed to be unnecessary.

What I claim as my invention is:

1. The method of refining sugar containing solutions, which comprises filtering a sugar containing solution of a certain density, and thereafter adding to the filtrate unfiltered values of the same material as in said filtrate in an amount calculated to substantially increase its density, whereby a solution is obtained of greater density and partially filtered. 70 75

2. The method of refining sugar containing solutions, which comprises filtering a sugar containing solution of a certain density with a filtering agent of low purifying power, and thereafter adding to the filtrate thus obtained unfiltered values of the same material, whereby a solution is obtained of greater density and partially filtered. 80 85

3. The method of refining sugar containing solutions which comprises filtering a sugar containing solution of a certain density with a filtering agent which has already been used for filtering a sugar containing solution, and thereafter adding to the filtrate thus obtained unfiltered values of the same material as in said filtrate in an amount calculated to substantially increase its density, whereby a solution is obtained of greater 90 95 density and partially filtered.

4. The method of refining sugar containing solutions, which comprises filtering a sugar containing solution of a certain density with an activated carbon of a relatively low degree of activation, and thereafter adding to the filtrate thus obtained unfiltered sugar values of the same material as in said filtrate in an amount calculated to substantially increase its density, whereby a solution is obtained of greater density which is partially filtered and partially decolorized. 100 105

5. The method of refining sugar containing solutions which comprises filtering a sugar containing solution of a certain density with an activated carbon which has already been used for filtering a sugar containing solution, and thereafter adding to the filtrate thus obtained unfiltered values of the same material as in said filtrate in an amount calculated to substantially increase its density, whereby a solution is obtained of greater density which is partially filtered and partially decolorized. 110 115

6. The method of refining sugar containing solutions which comprises filtering a sugar containing solution with a filtering agent which has already been used to filter a sugar containing solution of the same nature but of higher density, and thereafter adding to the filtrate thus obtained unfiltered values of the same material as in said filtrate in an amount calculated to substantially increase its density, whereby a solution is obtained of greater density and partially filtered. 120 125 130

7. The method of refining sugar containing solutions which comprises filtering a sugar containing solution with an activated carbon which has already been used to filter a sugar containing solution of the same nature but of higher density, and thereafter adding to the filtrate thus obtained unfiltered values of the same material as in said filtrate in an amount calculated to substantially increase its density, whereby a solution is obtained of greater density which is partially filtered and partially decolorized. 70
- 10 8. The method of refining sugar containing solutions, which comprises filtering a sugar containing solution of a certain density, adding to the filtrate thus obtained values of the same material as in said filtrate in an amount calculated to substantially increase its density, whereby a solution is obtained of greater density and partially filtered, and thereafter filtering the resulting partially filtered solution of increased density. 80
- 15 9. The method of refining sugar containing solutions, which comprises filtering a sugar containing solution of a certain density with a filtering agent of low filtering power, adding to the filtrate thus obtained values of the same material as in said filtrate in an amount calculated to substantially increase its density, whereby a solution is obtained of greater density and partially filtered, and thereafter filtering the resulting partially filtered solution of increased density with a filtering agent of relatively high filtering power. 85
- 20 10. The method of refining sugar containing solutions, which comprises filtering a sugar containing solution of a certain density with an activated carbon of a relatively low degree of activation, adding to the filtrate thus obtained values of the same material as in said filtrate in an amount calculated to substantially increase its density, whereby a solution is obtained of greater density and partially filtered and partially decolorized, and thereafter filtering the resulting partially filtered and partially decolorized solution of increased density with an activated carbon of a relatively high degree of activation. 90
- 25 11. The method of refining sugar containing solutions which comprises filtering a sugar containing solution of a certain density with a filtering agent which has already been used to filter a sugar containing solution, adding to the filtrate thus obtained values of the same material as in said filtrate in an amount calculated to substantially increase its density, whereby a solution is obtained of greater density and partially filtered, and thereafter filtering the resulting partially filtered solution of increased density with a filtering agent of maximum decolorizing power. 95
- 30 12. The method of refining sugar containing solutions which comprises filtering a sugar containing solution of a certain density with an activated carbon which has already been
- 35 used to filter a sugar containing solution, adding to the filtrate thus obtained values of the same material as in said filtrate in an amount calculated to substantially increase its density, whereby a solution is obtained of greater density and partially filtered and partially decolorized, and thereafter filtering the resulting partially filtered and partially decolorized solution of greater density with an activated carbon of maximum decolorizing power. 100
- 40 13. The method of refining sugar containing solutions which comprises filtering a sugar containing solution with a filtering agent which has already been used to filter a sugar containing solution of the same nature but of higher density, adding to the filtrate thus obtained values of the same material as in said filtrate in an amount calculated to substantially increase its density, whereby a solution is obtained of greater density and partially filtered, and thereafter filtering the resulting partially filtered solution of increased density with a filtering agent which has already been used to filter a solution of the same nature but of higher density. 105
- 45 14. The method of refining sugar containing solutions which comprises filtering a sugar containing solution with an activated carbon which has already been used to filter a sugar containing solution of the same nature but of higher density, adding to the filtrate thus obtained values of the same material as in said filtrate in an amount calculated to substantially increase its density, whereby a solution is obtained of greater density and partially filtered and decolorized, and thereafter filtering the resulting partially filtered and partially decolorized solution of increased density with an activated carbon which has already been used to filter a solution of the same nature but of higher density. 110
- 50 15. The method of refining sugar containing solutions which comprises filtering a sugar containing solution with a filtering agent which has already been used to filter a sugar containing solution of the same nature but of higher density, adding to the filtrate thus obtained values of the same material as in said filtrate in an amount calculated to substantially increase its density, whereby a solution is obtained of greater density and partially filtered, and thereafter filtering the resulting partially filtered solution of increased density with a filtering agent of maximum decolorizing power. 115
- 55 16. The method of refining sugar containing solutions which comprises filtering a sugar containing solution with an activated carbon which has already been used to filter a sugar containing solution of the same nature but of higher density, adding to the filtrate thus obtained values of the same material as in said filtrate in an amount calculated to substantially increase its density, whereby a solution is obtained of greater density and
- 60 120
- 65 125
- 70 130

partially filtered and decolorized, and thereafter filtering the resulting partially filtered and partially decolorized solution of increased density with an activated carbon of maximum decolorizing power.

5 17. The method of refining sugar containing solutions which comprises filtering a sugar containing solution of a certain density with a filtering agent which has already been used to filter a sugar containing solution, adding to the filtrate values of the same material as in said filtrate in an amount calculated to substantially increase its density, whereby a solution is obtained of greater density and 10 partially filtered, and thereafter filtering the resulting partially filtered solution of increased density with a filtering agent of relatively higher power which has already been used to filter a sugar, syrup, affinates or other "run-offs," or molasses solution.

15 18. The method of refining sugar containing solutions, which comprises filtering a sugar containing solution of a certain density with an activated carbon which has already been used to filter a sugar containing solution, adding to the filtrate thus obtained values of the same material as in said filtrate in an amount calculated to substantially increase its density, whereby a solution is obtained of greater density and partially filtered and partially decolorized, and thereafter filtering the resulting partially filtered and partially decolorized solution of increased density with an activated carbon of 20 relatively high power which has already been used to filter a sugar containing solution.

25 In testimony, whereof, I have signed my name to this specification this 16th day of February, 1926.

30 40 E. N. EHRHART.
